UNITED STATES PATENT OFFICE.

AMEDEO LUCHETTI, OF MONERO, NEW MEXICO.

RAILWAY-TRACK.

1,348,286.

Specification of Letters Patent. Patented Aug. 3, 1920.

Application filed April 19, 1918. Serial No. 229,547.

To all whom it may concern:

Be it known that I, AMEDEO LUCHETTI, a citizen of the United States, residing at Monero, in the county of Rio Arriba and State of New Mexico, have invented certain new and useful Improvements in Railway-Tracks; and I do hereby declare the following to be a full, clear, and exact description of the invention, such as will enable others skilled in the art to which it appertains to make and use the same.

This invention relates to certain new and useful improvements in railway track construction, and contemplates more especially an improved type of rail supporting tie and associated rail joining device.

An object of the present invention is the production of a readily portable rail tie and joint designed especially for use in temporary track construction such as that employed in mines, narrow gage lines, building construction and the like. Lightness in weight and rapidity in assembling being principal factors in work of this kind; the herein described invention has been produced to supply these needs in an effective manner.

Another object of this invention is the production of a metallic tie of durable and light construction having formed thereon a rail engaging member adapted to coöperate with a rail engaging one-piece securing device of wedge-like formation detachably secured to the tie.

With these and other objects in view the invention further consists in the arrangement and design of the several parts hereinafter described and pointed out in the appended claims.

In the accompanying drawings, which show by way of illustration an embodiment of my invention,

Figure 1 is a view in elevation of my improved tie and rail joint as applied in supporting one rail member of a railway track.

Fig. 2 is a plan view thereof illustrating the manner in which the abutting ends of two rail sections are brought together and secured in position upon my improved tie, and

Fig. 3 is a sectional view on the line 3—3 of Fig. 2 showing in elevation the coöperating one-piece rail engaging member.

The invention while primarily designed for use in the construction of light railroads which can be readily taken up and removed

to other fields of operation, is not so limited, and it will be readily understood that it may be equally applied to the construction of relatively permanent lines of transportation.

Referring to the drawings in which similar reference characters designate corresponding parts, the tie 1 is formed of any suitable metal capable of sustaining a predetermined load. The tie 1 is grooved throughout its length as shown at 2, the purpose of said groove being to form oppositely disposed edges 3 of wedge-like construction capable of biting into the surface upon which the track is laid, thereby giving definite stability to the track.

Near the ends of each tie and formed integrally therewith, are rail engaging members 4. Each of these members 4 comprises extending arms 5 projecting beyond the sides of the tie as shown in Fig. 2. The inner face 6 of the rail engaging member is designed to fit between the head and base of the rail. The under face 7 of the rail engaging member 4 is angularly cut to conform to the taper of the upper surface of the flange of the rail. A recess 8 is provided in the tie 1 and forms a flat surface upon which the rail rests. Between the under face 7 of the rail engaging member 4 and the rail supporting surface of the tie the rail is firmly positioned and secured in place by a one-piece coöperating rail engaging member 9, now to be described.

The one-piece rail engaging member 9 is provided with extending arms 10 of a length equal to the arms 5 of the rail engaging member 4. The under face of the rail engaging member 9 is angularly cut or inclined to conform to the upper surface of the flange of the rail, as shown in Fig. 1. Formed integrally with the one-piece rail engaging member 9 is a wedge portion 11 adapted to rest upon the supporting surface of the tie and coöperate with an inclined shoulder 12 extending across the tie 1. The purpose of this inclined shoulder 12 and coöoperating wedge portion 11 is to insure the forcing of the rail engaging member 9 against the web of the rail and the said web in turn against the rail engaging member 4.

The securing device for holding the wedge portion in place upon the tie comprises a threaded bolt or locking screw 13 threaded into the body of the tie 1. The screw 13

passes through an opening formed in a depending flange or shoulder 14 carried by the rail engaging member 9, and is provided with a head 15, as shown. The depending flange or shoulder 14 is preferably adapted to abut against the side of the tie as shown in Fig. 3 when the rail ends are clamped in position. An extension arm 16 of the flange 14 protrudes outwardly under the rail, and 10 serves to guide the coöperating rail member 9 and retain it on the tie.

In assembling the railway track, the abutting ends 17 and 18 of joining rails sections are brought together upon the tie, as shown 15 in Fig. 2. These abutting ends of the rails may be in the stepped form as indicated at 19, or they may be of any other approved form. The flanges of the base of the rails are snugly fitted in the recess 8 and under 20 the inclined surface of the rail engaging member 4. The coöperating rail engaging member 9 is now applied with its inclined surface engaging the opposite flanges of the rails, and its wedge portion 11 against the 25 inclined shoulder 12 formed on the tie 1.

The screw bolt 13 is now inserted through the depending flange 14 and threaded into the tie. As the screw 13 is tightened the wedge portion 11 of the rail engaging member 9 is gradually forced against the inclined shoulder 12 of the tie, thereby pressing the 30 said rail engaging member against the rail and more particularly the web thereof. The continued tightening of the screw acts to 35 force the rail ends over against the rail engaging member 4 and insure a complete securing of the rails in place.

From the foregoing it will be obvious that an efficient tie and rail joint has been produced in which tie or fish plates, spikes and numerous other elements now used are entirely dispensed with, and a novel single or one-piece rail securing member is substituted.

45 Advantages in handling, laying and transporting this form of track construction will also be apparent.

I claim:

1. In a track construction of the class described the combination with a rail supporting tie provided with a relatively fixed rail engaging member, of a coöperating rail engaging member movable on said tie, a wedge portion provided on said coöperating rail 50 engaging member, an inclined shoulder formed on said tie, a flange provided on said coöperating rail engaging member and adapted to bear upon the under side of the rail, and a screw adapted to pass through 55 said flange and into the tie for forcing the

aforesaid wedge against the inclined shoulder for clamping the rail ends in position upon the tie.

2. In a track construction of the class described the combination with a rail supporting tie provided with a relatively fixed rail engaging member, of a coöperating rail engaging member movable on said tie, a wedge portion provided on said coöperating rail 65 engaging member, an inclined shoulder formed on said tie, a flange provided on said coöperating rail engaging member and adapted to bear upon the under side of the rail, and means located upon one side of the tie and carried by said flange for forcing the 70 aforesaid wedge against the inclined shoulder for clamping the rail ends in position upon the tie.

3. A railway track construction comprising a tie, a rail receiving recess formed on the upper surface of said tie, a rail engaging member formed integrally with said tie and having its under surface inclined for engaging the flange of the rail, another rail engaging member movable on said tie and having its under face inclined for engaging the upper face of the flange of the rail, an arm formed thereon and adapted to bear upon the under side of the rail, a wedge portion formed on said last mentioned rail engaging member, an inclined shoulder formed integrally with the tie and against which the wedge portion bears, and means carried by the aforesaid arm for holding said wedge portion against the inclined shoulder for securing the ends of the rails in position. 85

4. A railway track construction comprising a tie having a rail receiving recess, a rail engaging member provided on the said tie, a coöperating rail engaging member 100 movable in said recess, an arm carried by said last mentioned rail engaging member adapted to bear upon the under surface of the rail for retaining said rail engaging member in said recess, a wedge portion 105 formed on said movable rail engaging member, an inclined shoulder formed on one edge of the aforesaid recess in the tie, and a locking device positioned upon one side of the tie and carried by said second mentioned coöperating rail engaging member for securing the said member against the inclined shoulder and rail support. 110

In testimony whereof I affix my signature in presence of two subscribing witnesses.

AMEDEO LUCHETTI.
